[57] **CLAIM**

The ornamental design for a shoe sole, as shown and described.

DESCRIPTION

FIG. 1 is a bottom plan view of a shoe sole showing an alternate embodiment of our new design;
 FIG. 2 is a left side view thereof;
 FIG. 3 is a right side view thereof;
 FIG. 4 is a front elevational view thereof; and,
 FIG. 5 is a rear elevational view thereof.
 The broken line showing of a shoe upper in FIGS. 1-5 is environmental only and forms no part of the claimed design.
